[57] CLAIM

The ornamental design for a pocket unit for attachment to a beach chair, as shown and described.

DESCRIPTION

FIG. 1 is a front elevational view of the pocket unit for attachment to a beach chair showing my new design; FIG. 2 is a rear elevational view thereof; FIG. 3 is a left side elevational view thereof; FIG. 4 is a right side elevational view thereof; FIG. 5 is a top plan view thereof; FIG. 6 is a bottom plan view thereof; and, FIG. 7 is an enlarged front elevational view showing a use thereof.

The broken line showing of a beach chair, in FIG. 7, is for illustrative purposes only and forms no part of the claimed design. The criss-cross shading in FIGS. 1-7, represents fabric, and is understood to extend throughout the pocket unit.
